UNITED STATES PATENT OFFICE.

GEORG M. VON HASSEL, OF NEW YORK, N. Y., ASSIGNEE, BY MESNE ASSIGNMENTS, TO AMERICAN SUSPENSION RAILWAYS COMPANY, OF DOVER, DELAWARE, A CORPORATION OF DELAWARE.

SUSPENSION-RAILROAD WITHOUT TRACTION-CABLE.

1,122,000.

Specification of Letters Patent. Patented Dec. 22, 1914.

Application filed October 16, 1912. Serial No. 726,169.

To all whom it may concern:

Be it known that I, GEORG M. VON HASSEL, civil engineer, a citizen of Germany, residing at New York, in the county of New 5 York and State of New York, have invented a new System of Suspension-Railroad Without Traction-Cable, of which the following is a specification.

This invention relates to an improvement 10 in suspension railways, more particularly a monorail system, the object of the invention being to provide a novel monorail or suspending device arranged to assist in the transportation of the car or wagon hung 15 thereupon, the car furnishing its own traction power.

By means of my improved monorail system traction cables are obviated and a line of indefinite length can be constructed as I 20 do not depend upon any element other than the rail and power carried by the car together with an intermediate element which is actuated by the power within the car and which acts upon the rail direct.

25 I will now proceed to describe my invention in detail in connection with the accompanying drawings, to which reference is had, and in which—

Figure 1 is a side elevation illustrating a 30 suspended car and a portion of a monorail embodying my improvement; Fig. 2 is a vertical cross-section thereof; Fig. 3 is a detail view of the driving or power exerting mechanism. Fig. 4 is a similar view illustrating the power mechanism in combination with a smooth surface rail; Fig. 5 is a 35 plan view of the rail with branch rails; Fig. 6 is a detail view, illustrating a modified form of rail support.

40 As herein illustrated my improvement consists of a suspended rail or cable *a* provided with a continuous spiral or thread *b*. To force the car ahead I provide a rotatable nut or spiral mechanism *c*. To facilitate the rotation of the nut *c* and to advance the car I provide the same with rollers or wheels *d*, the said rollers bearing against the smooth surface of the rail *a* and threads *b* and act as ball or roller bearings as well as an element of a nut. Each end of the nut or spiral *c* is provided with plates *e* which carry the power transmitting medium. One surface of each plate *e* is provided with a rail (not shown) against which wheels or

rollers *f* bear, the said rollers acting to support the car through the braces *h*, that is to say, the shaft of each roller *f* supports its adjacent end of the car. Motion is transmitted to the spiral or nut *c* through suitably supported gears *g* actuated by the motor at *i* and gears, meshing with the gears *g*, carried by the plates *e*. When the gears *g* are rotated the plates *e* and nut *c* will also rotate, causing the car to advance along the rail, the car hanging on the shafts of the 65 rollers *f*, the weight being taken by the rail on the adjacent surface of the plates *e*. In other words, the rollers *f* hang upon the rails carried by the plates *e*. When the plates *e* and nut *c* are rotated the rollers *f* 70 will revolve upon the axis of the shaft which supports the car, the weight of the car acting to keep the rollers from rotating around the axis of the rail *a*. The gears *g* may be rotated by any suitable device, in this instance, by pulleys *r r* which are rotated by the motor *i* (Fig. 3). To support the monorail, I provide, at intervals, suspension rods *h*, carried by supporting posts *g'*. The plates *e* are provided with slots *m* which allow for the passage of the rods *h*. The distance between the rods *h* will be such that a certain number of revolutions of the nut *c* will cause the slot *m* to align with the said rods. For instance, at the completion of a 85 revolution the slot *m* will be in a vertical position, and a rod *h* will be located say for instance, at every twenty threads or turns of the spiral *b*. It is obvious that the rods *h* will pass through the slots *m* if the said rods 90 are located substantially at the top of a thread, at which point the slots *m* will be in a vertical position. The braces *h* may be of relatively thin material.

95 *s* is a support having the form of a tube provided on its bottom with a longitudinal slit *t*; the object of this slit is to permit the passage of the rod-system on which the wagons are suspended. The diameter of this tube *s* must be larger than the diameter of the locomotion-mechanism *c*, in order to permit the free passage of the latter through the tube *s*. If this support *s* is employed, the slot *m* on the front plates *e* can be dispensed with.

100 Although I have shown supporting posts *g'* for suspending the device, I may instead of this form of support employ a simple ar-

angement of support such as is shown in dotted lines *p* in Fig. 2.

In Fig. 5 is shown a plan view of the rail with branch rails, the reference characters 5 in said figure indicating similar parts to those described for the other views, *w w* indicating the branch rails.

What I claim and desire to secure by Letters Patent is:

- 10 1. In a suspension rail-way, a rail, a rotatable propelling device suspended on said rail, means carried by and projecting beyond the surface of the rail adapted to facilitate the advance of the propelling device, and a car suspended from said propelling device, said propelling device being rotatable at an angle to the axis of the shaft.
- 15 2. In a suspension rail-way, a rail, a continuous thread or spiral carried by the rail, a rotatable nut carried by and projecting beyond the surface thereof the rail and engaging the spiral thereupon, a car suspended from said nut, and means to rotate said nut.
- 20 3. In a suspension rail-way, a rail, supports for said rail, spaced at intervals throughout the length thereof, supports for said rail supports, threads carried by said rail, a rotatable nut carried by said rail, and engaging the threads thereupon, a plate located at each end of said nut provided with a slot for the passage of said rail supports, a car, suspended from said nut, and means to rotate said nut.
- 25 4. In a suspension rail-way, a suspended rail, a thread carried by the rail, suspending devices carried by the rail adapted to sup-

port the object to be moved, propelling means in engagement with the thread on said rail adapted to advance the suspended object, and means to actuate the propelling means.

5. In a suspension railway, a rail, the surface of the rail being spirally formed, a rotatable nut engaging the spiral surface of the rail, a plate carried by each end of said nut, a rail mounted on the outer surface of each plate, rollers bearing against said rail, braces supporting said rollers, a car carried by said braces, and means to rotate said plates.

6. In a suspension railway, a rail, the surface of the rail being spirally formed, a rotatable nut engaging the spiral surface of the rail, a plate carried by each end of said nut, a rail mounted on the outer surface of each plate, rollers bearing against said rail, braces supporting said rollers, a car carried by said braces, gears carried by the car, a gear carried by each plate in mesh therewith, and means to rotate said gears.

7. In a suspension railway, a rail, a thread carried by the rail, a rotatable nut engaging said thread, a plate carried by each end of said nut, a rail mounted on the outer surface of each plate, rollers bearing against said rail, braces supporting said rollers, a car carried by said braces, and means to rotate said plates.

GEORG M. von HASSEL.
